UNITED STATES PATENT OFFICE.

FRED E. LEE, OF DOWAGIAC, MICHIGAN.

DESIGN FOR A STOVE FENDER OR RAIL.

SPECIFICATION forming part of Design No. 30,507, dated April 4, 1899.

Application filed February 13, 1899. Serial No. 705,445. Term of patent 14 years.

To all whom it may concern:

Be it known that I, FRED E. LEE, a citizen of the United States, residing at the village of Dowagiac, in the county of Cass and State 5 of Michigan, have invented a certain new and useful Design for a Stove Fender or Rail, of which the following is a specification.

This invention relates to a new and original design for a stove fender or rail.

10 The design is fully illustrated in the accompanying drawing, forming a part of this specification, in which the view shown is a front perspective view of a stove fender or rail embodying my new design.

15 As shown in the drawing, the leading or material features of my new design consist of a fender or rail representing a section of a tree

or branch having two diverging parts at either end, which are the means of attaching to the stove. In the center is a monogram. Sprays 20 of leaves are configured thereon, as shown. The surface configuration is that of the bark of a tree.

Having thus described my invention, what I claim as new, and desire to secure by Letters 25 Patent, is—

The design for a stove fender or rail as herein described and shown.

In witness whereof I have hereunto set my hand and seal in the presence of two witnesses. 30

FRED E. LEE. [L. S.]
